UNITED STATES PATENT OFFICE.

GEORGE MAXWELL CLAGETT AND SARAH CHELSEA CLAGETT, OF BROOKLYN, NEW YORK.

ATTACHMENT FOR WELSBACH OR SIMILAR GAS-BURNERS.

SPECIFICATION forming part of Letters Patent No. 734,668, dated July 28, 1903.

Application filed May 14, 1903. Serial No. 157,142. (No model.)

To all whom it may concern:

Be it known that we, GEORGE MAXWELL CLAGETT and SARAH CHELSEA CLAGETT, citizens of the United States, residing at No. 409 5 Third street, Brooklyn, in the county of Kings and State of New York, have invented certain new and useful Improvements in Attachments for Welsbach or Similar Gas-Burners, of which the following is a specification, reference being 10 had therein to the accompanying drawings.

Our invention relates to gas-burners of the Welsbach type; and the object of the same is to provide means to be associated with the ordinary fixture to prevent the mantle, which 15 forms the incandescing medium, from partaking of any vibratory movement to which the gas-fixture may be subjected, and thereby prevent the bottom or unsupported end of the mantle from striking against the contiguous 20 portion of the burner and by reason of the jar received from such impact breaking or cracking, and for supporting the same near its lower end for other purposes.

To this end the invention includes the combination and arrangement of component parts, to be hereinafter described, and particularly pointed out in the claims.

While the invention is susceptible of various modifications, we have illustrated in the 30 accompanying drawings and shall hereinafter describe what is now conceived to be the preferred embodiment of the same.

In the drawings, Figure 1 is a side elevation of a gas-fixture embodying our invention. Fig. 2 is a detail plan view, and Fig. 3 is a detail view of the attachment separated from the fixture.

As is well known, the mantles used in the Welsbach type of incandescent burner are 40 constructed of extremely fragile material, and such mantles are usually suspended at their upper ends from a wire support, while their lower ends, which extend over the mixing tube or burner proper, are entirely unsupported. The lower ends of the mantles in order to fit easily about the burners are made of greater diameter than the latter, and as 45 said mantles are suspended, as premised, at their upper ends heretofore when the fixture 50 has been subjected to vibration the same has been transmitted to the lower end of the man-

tle, causing the same to strike against the burner. The striking of the mantle against the burner subjects the former to a jarring action, which is liable to rupture or break 55 the same, and, as has been found in actual practice, many mantles are destroyed in this manner.

In our present invention means are provided for steadyng the lower end of the mantle to 60 prevent the vibration of the same and for other purposes, such means being so constructed as to engage the unsupported portion of the mantle firmly yet lightly, so as to avoid fracture thereof.

The means disclosed in the drawings for effecting the ends sought include generally a part for engagement with the mixing or burner tube, a part or plurality of parts for engagement with the mantle at the lower portion of the same, and a flexible arm carrying 70 each of the parts engaging the mantle, having means associated with the same for adjusting its position.

In the accompanying drawings the mixing 75 or burner tube is indicated by the letter *a*, the mantle by the letter *b*, and the wire support therefor by the letter *c*.

The means for engaging the mantle for steadyng the same in the present exemplification of our invention include a base portion 80 *d*, surrounding and embracing the tube *a*, and oppositely-arranged segmental members *e* for engagement with the exterior of the mantle at the lower portion or end of the 85 same. Each member *e* is connected to and supported from the base portion *d* by a flexible or yielding arm *f*.

The present invention contemplates equipping the conventional form of Welsbach 90 burner now in common use with the mantle-steadying means, and to this end the base *d* is preferably formed by a split corrugated ring or section of a ring, the ends of which are designed to be spread to permit the steadier 95 to be applied to the mixing-tube and when freed to contract to engage the tube, and thereby frictionally hold the steadier in place thereon.

In order that the members *e*, which engage the mantle, may be accurately fitted to the lower portion or end of the latter, so as 100

to firmly yet lightly make contact therewith, the arms *f* are provided with means for adjusting them radially in reference to the burner or to and from the sides thereof. To 5 this end each arm is preferably provided with a screw, the inner end of which finds a bearing against the outer periphery of tube *a* or other contiguous appliances of the burner.

The mantle is fitted to the fixture in the 10 usual way, being supported at its upper end upon the angular-bent end of the wire *c* and having its lower end passed over the upper end of the tube *a*. In order that the said lower end may be properly fitted to the tube, 15 the members *e* are spread a distance apart, and after the mantle is properly suspended the screws *g* are manipulated to permit the tension of the arms *f* to move the members *e* inwardly until the latter lightly engage the 20 lower portion or end of the mantle.

While in the present exemplification of our invention we have shown two segmental engaging members *e*, as will be understood said members may be formed integral.

25 In applying the steadyng device to the burner the same is preferably so placed as to bring the supporting-wire *c* in the space between the ends of the members *e*.

The construction and operation of our invention will be readily understood upon reference to the foregoing description and accompanying drawings, and it will be appreciated that the parts and combinations recited may be varied within a wide range without departing from the spirit and scope 35 thereof.

What we claim as new, and desire to be secured by Letters Patent, is—

1. The combination with a fixture, comprising a burner-tube and a mantle freely supported at its upper end, of means for steadyng the lower portion of the mantle, comprising a base supported upon the burner-tube, and segmental members engaging the 40 lower portion of the mantle supported from said base, substantially as described.

2. The combination with a fixture, comprising a burner-tube and a mantle freely supported at its upper end, of a steadyng

device comprising a base fitted to the burner, 50 segmental engaging members coacting with the lower portion of the mantle, and yielding arms interposed between said members and said base, substantially as described.

3. The combination with a fixture, comprising a burner-tube and a mantle freely supported at its upper end, of a steadyng device comprising a base fitted to the burner, segmental engaging members coacting with the lower portion of the mantle, and means 60 for adjusting said segmental engaging portions radially of the burner, substantially as described.

4. The combination with a fixture, comprising a burner-tube and a mantle freely 65 supported at its upper end, of a steadyng device comprising a base fitted to the burner, segmental engaging members coacting with the lower end of the mantle, yielding arms carrying said members, and means for adjusting said engaging members radially of the burner, said means comprising screws carried by said arms, the inner ends of which find bearings upon the burner-tube, substantially as described. 70

5. A steadyng device for incandescing mantles of gas-burners, comprising a base portion formed of a yielding ring-section, oppositely-arranged segmental mantle-engaging members, and spring-arms formed integral 80 with said section and base portion interposed between the same, substantially as described.

6. A steadyng attachment for gas-burners, provided with incandescing mantles, comprising a sectional ring, vertical yielding 85 arms extending from opposite sides thereof and formed integral therewith, and horizontally-disposed sectional engaging members surmounting said arms, substantially as described.

90 In testimony whereof we affix our signatures in the presence of two witnesses.

GEORGE MAXWELL CLAGETT.
SARAH CHELSEA CLAGETT.
